CLAIM

The ornamental design for a wireless remote control, as shown and described.

DESCRIPTION

FIG. 1 is a perspective view of a wireless remote control showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a rear side perspective view thereof;

FIG. 9 is an enlarged detail view of area 9 shown in FIG. 1; FIG. 10 is an enlarged detail view of area 10 shown in FIG. 2; and,

FIG. 11 is an enlarged detail view of area 11 shown in FIG. 3.

Any shading and cross-hatching are not features of the design but are utilized to illustrate the surface contours of the wireless remote control design in the drawings.

The broken lines showing portions of the article, and the broken lines indicating where the enlargements have been taken from no part of the claimed design.
